ALARM BELL FOR WINDOWS, DOORS, ETC.

Alfred R. Euler, New York, N. Y.

Application February 21, 1948, Serial No. 10,047

5 Claims. (Cl. 116—90)

1

This invention relates to new and useful improvements in rotary bells, of the kind which may be employed, for instance, for giving an audible alarm that a housebreaking attempt is being made. Rotary bells have other uses, such as those mentioned in U. S. Letters Patent No. 2,417,297, issued to me on March 11, 1947; and it is contemplated that the improvements of the present invention may be used in any or all of these connections.

A rotary bell, as pointed out in said patent, is one in which the bell is sounded by rotation of a handle or wheel; and the rotary bell of said patent, embodied as a burglar alarm, is characterized by certain novel and valuable features, among which are a ringing of the bell regardless of the speed at which its rotating parts are turned, the giving of this signal regardless of in which direction said rotating parts are turned, and generally a simple and reliable mechanism, in combination with means for permitting easy installation of the device on windows, doors, drawers of cash registers and the like.

The object of the present invention is to retain the above and other advantages of the concept of said patent, and yet further simplify the device, while strengthening the working parts thereof, reducing the cost of manufacture of various parts, and making easier the assembly of all the parts.

According to the present invention, a combination of parts is provided wherein, for one thing, there is substituted, for what is called the cross-bar of the construction shown in said patent, an easily fabricable plate or strap, which may be a metal stamping; and which strap, although a non-rotative part as is said cross-bar, is secured, not to a fixed post (called the shaft in said patent), but, instead, to a fixed planiform element forming the circular top of a hub formation of comparatively large diameter upstanding from a mounting bracket for the device. While a fixed post is used, this for mounting the non-rotative bell-cup, the casing of the device, this constituting its main rotatable part, has a large central circular aperture sleeving such hub, thereby permitting said casing to be rotatably mounted on the bracket in a way to properly hold the parts to rigidly maintained relative dispositions while permitting easy rotation of the casing on the bracket.

Also according to the present invention, for another thing, a single spring means, this preferably a coil spring, for resiliently biasing a plurality of clapper or hammer carrying pivoted

2

arms, is substituted for a plurality of leaf springs one for each of the said arms.

Further according to the present invention, for another thing, said arm is of an improved construction, particularly in regard to the mounting means provided on the arm for an element designated in said patent a tiltable member. Thereby, also, there is permitted to be used a more rugged tiltable member; there is eliminated the necessity for stop pins for limiting the amplitude of oscillation of said tiltable member; and there is permitted an improved construction for a circularly arranged plurality of spaced elements carried by the casing for coacting with an arm's tiltable member to cause ringing of the bell during turning of the casing.

Said elements are projections upstanding from the rotatable part just referred to, this part being said casing. According to said patent, 20 these projections, which should be of small diameter, are pins having to be given a considerable height; whereas, according to the present invention, said projections may be of relatively low height, due to the fact that a tiltable member 25 may have its field of oscillation in a plane so close to the wall of the casing from which the projections extend that the bottom of the tiltable member may actually be in contact with said wall.

Because of the advantage last-mentioned, said 30 projections may be provided as low teats formed up from and integral with the casing.

Various other simplifications and improvements will be pointed out or become apparent hereinafter.

35 For further comprehension of the invention, and of the objects and advantages thereof, reference will be had to the following description and accompanying drawings, and to the appended claims in which the various novel features of the 40 invention are more particularly set forth.

In the accompanying drawings forming a material part of this disclosure—

Fig. 1 is a fragmentary elevational view, showing 45 a window of the sliding sash type, equipped with a device constituting an embodiment of the invention as now favored.

Fig. 2 is, on a somewhat enlarged scale, a vertical section taken on the line 2—2 of Fig. 1.

Fig. 3 is a top plan view of said device, with 50 the bell-cup removed.

Fig. 4 shows the parts of Fig. 3 in perspective.

Fig. 5 is a transverse vertical section, taken on the line 5—5 of Fig. 3.

Fig. 6 is a perspective view showing the strap 55 aforesaid.

Fig. 7 is a similar view showing one of the arms aforesaid.

Fig. 8 is a similar view showing one of the tiltable members aforesaid.

Fig. 9 is an axial sectional view through the casing.

Fig. 10 is a view similar to Fig. 7, showing a modification of said arm.

Referring to the drawings more in detail, and first to Figs. 1 and 2, a window is illustrated having an upper sliding sash 15, guided between rails 16 and 17, a lower sliding sash 18, guided between the rail 17 and a rail 19, and a window-frame 20 on which the rails 16, 17 and 19 are mounted.

The device pursuant to the invention, marked as a whole 21, is here illustrated as of the type adapted to be secured to either of the sashes 15 or 18. Said device is shown as secured to the lower sash 18. This securing is by means of a spring in the form of a substantially L-shaped strip of spring steel 22, attachable by use of screws 23. Said spring is normally resiliently biased, as indicated at 22a in Fig. 2, so that when the screws 23 are tightly applied, the device 21 will bear, at a knurling or other roughage on the external cylindrical surface of a cup-like casing 24, and with some pressure, against the upper sash 15; said casing being rotatively mounted on an L-shaped bracket 25 riveted to the spring 22 as at 26.

Thus when either the upper sash 15 is lowered or the lower sash 18 is raised, the casing 24 will be rotated.

Referring to Figs. 3-7, the main portion of the bracket 25 is circularly upset to provide a low cylindrically upstanding hub formation 27, and a post 28 is riveted at its bottom to said bracket (see Fig. 5), so as to extend upward fixedly from the center of such hub.

Due to the hub 27, the casing 24, apertured at its center, as shown in Fig. 9, to the same diameter as that of said hub, and sleeving the hub at said aperture, may be given a most advantageous journalling support on the bracket 25; once the aforesaid strap, this marked 30, is attached to the hub 27. This attachment may be spot welded, or, as here shown, by rivets 31, the shanks of which traverse apertures 32 (Fig. 6) through said strap. Where spot welding is used, the apertures 32 will be omitted. This strap has reduced opposite end extensions 33 having downturned lips 34, these extensions are apertured at 35, and midway along the length of the strap it has an aperture 35a for engaging about the post 28. The bottoms of the lips 34 engage the outer limits of the casing as shown in Fig. 5.

For reception by the apertures 35 of the strap 30 there are trunnions 36, formed upon arms 37. Two of these arms are provided, each oscillably mounted by way of its trunnion 36 in one of the apertures 35 of the strap 30.

Each of these arms 37 has oscillably mounted thereon a tilttable member 39 for coaction with pin-like projections 40 arranged in uniformly spaced relation along a circle concentric with the axis of rotation of the casing 24 and integrally formed up from said casing. These projections 40 may be quite short, as the members 39 have their undersides in face-wise contact with the casing.

Each tilttable member 39, moreover, instead of being an attenuated, almost needle-like element as in said patent, is of substantially equilateral-triangular outline, so that ample strength and long life against wear are assured. Each member 39 is oscillably mounted on its arm 37, by

means of an integral pin 41 formed on each tilttable member 39, with such pin 41 received in the aperture 42a of said arm. Further, the opposite sides of the broad base of a member 39 coact with downbent portions of its carrying arm (which portions, marked 43 and 44 in Fig. 7, constitute the ends of a hump 42), to provide stops for limiting the amplitude of oscillation of said member 39; giving a much simplified, less expensive and more rugged construction for the purpose.

The terminal portions 33-34 of the strap 30 (Fig. 6), providing humps analogous to the humps 42, coact at their lips 34 with shoulders presented by lateral projections 45 from the arms 37, in providing stops for limiting the amplitude of oscillation of the arms 37, which carry the clappers or hammers. Said hammers are merely terminal disc-like enlargements 46 at the ends of the arms remote from their tilttable members 39.

In order resiliently to urge both arms 37 to swing their ends carrying the tilttable members 39 inward toward the projections 40 upstanding from the casing 24, a single coil spring 47 is all that is employed; this connected at opposite ends to hooks 48 one formed up from each arm 37.

The post 28 has an upper reduced threaded extension 48, for carrying the bell-cup 49; the latter having a central aperture through which said extension passes. The bell-cup is secured on the post by way of a nut 50, either a separate piece or forming part of the bell-cup, and having an internal thread matching that of the extension 48.

As in said patent, the tilttable members 39 snap into and out of engagement with one projection 40 and then enter between the next pair of said projections, during rotation of the casing 24 in either direction, and so, for each revolution of said casing, both hammers 46 sharply strike the bell-cup as many times as there are projections 40 present.

Referring to Fig. 10, the modified form of arm here shown, and marked as a whole 37', has elements 36', 42', 42a', 43', 44', 45', and 48' respectively corresponding to the portions 36, 42, 42a, 43, 44, 45 and 48 of an arm 37. The arm 37' is made of spring steel, and carries a suitably added piece constituting a hammer. Such hammer may be a stud riveted to the arm at the end thereof opposite to its end provided with the hump 42'. A short portion of the length of the arm is substantially perpendicularly upwardly bent as at 51, and at an intermediate point along the arm between said bend and the hammer, the arm is twisted through 90° as at 52 so as to add a mounting of extra resiliency for the hammer.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A rotary bell comprising, an L-shaped bracket provided centrally with an upset hub portion, a resilient member for supporting said bracket on a window, a cup-like casing rotatably mounted on said L-shaped bracket and provided externally thereof with knurled roughage, a shaft non-rotatably secured centrally to said bracket to extend vertically therefrom, an elongated strap member mounted intermediate

of its ends on said vertical shaft and secured to the hub of said bracket with the ends thereof overlying said casing, a pair of arcuate arms pivotally mounted on said strap member, a tiltable member mounted on one end of each of said arcuate arms and on opposite sides of said strap, resilient means interconnecting said arms at points adjacent their attachment to the tiltable members, a clapper hammer formed on the other end of each of said arcuate arms, and projections formed integrally with said casing to project upwardly therefrom and arranged in a circle concentric with said vertical shaft and in abutting alignment with the tiltable members mounted on said arms for the purpose described.

2. In a bell, a bracket formed with a circular projecting hub portion, a cup-like casing formed with a central opening through which said hub portion projects for rotatively supporting said casing on said bracket, an elongated strap member secured to said hub portion and overlying the inner face of said casing rotatively retaining said casing in position on said hub portion, arcuate arms pivotally supported intermediate of their ends upon the ends of said strap member, a clapper formed on one end of each of said arcuate arms, resilient means interconnecting said arms on the sides of said pivots opposed to the ends of said arms formed with said clappers, projections formed on said casing between said arcuate arms and said hub portion to turn with said casing when said casing is rotated relative to said bracket, and a tiltable member mounted on the other end of each of said arcuate arms to be successively engaged by said projections as said casing rotates to successively pivot said arms against the action of said resilient means.

3. In a bell, a bracket formed with a circular projecting hub portion, a cup-like casing formed with a central opening through which said hub portion projects for rotatively supporting said casing on said bracket, an elongated strap member secured to said hub portion and overlying the inner face of said casing rotatively retaining said casing in position on said hub portion, arcuate arms pivotally supported intermediate of their ends upon the ends of said strap member, a clapper formed on one end of each of said arcuate arms, resilient means interconnecting said arms on the sides of said pivots opposed to the ends of said arms formed with said clappers, projections formed on said casing between said arcuate arms and said hub portion to turn with said casing when said casing is rotated relative to said bracket, and a tiltable member mounted on the other end of each of said arcuate arms to be successively engaged by said projections as said casing rotates to successively pivot said arms against the action of said resilient means, said resilient means comprising a contraction spring.

4. In a bell, a bracket formed with a circular projecting hub portion, a cup-like casing formed with a central opening through which said hub portion projects for rotatively supporting said casing on said bracket, an elongated strap mem-

ber secured to said hub portion and overlying the inner face of said casing rotatively retaining said casing in position on said hub portion, arcuate arms pivotally supported intermediate of their ends upon the ends of said strap member, a clapper formed on one end of each of said arcuate arms, resilient means interconnecting said arms on the sides of said pivots opposed to the ends of said arms formed with said clappers, projections formed on said casing between said arcuate arms and said hub portion to turn with said casing when said casing is rotated relative to said bracket, and a tiltable member mounted on the other end of each of said arcuate arms to be successively engaged by said projections as said casing rotates to successively pivot said arms against the action of said resilient means, and means for restraining the action of said resilient means in pivoting said arcuate arms.

5. In a bell, a bracket formed with a circular projecting hub portion, a cup-like casing formed with a central opening through which said hub portion projects for rotatively supporting said casing on said bracket, an elongated strap member secured to said hub portion and overlying the inner face of said casing rotatively retaining said casing in position on said hub portion, arcuate arms pivotally supported intermediate of their ends upon the ends of said strap member, a clapper formed on one end of each of said arcuate arms, resilient means interconnecting said arms on the sides of said pivots opposed to the ends of said arms formed with said clappers, projections formed on said casing between said arcuate arms and said hub portion to turn with said casing when said casing is rotated relative to said bracket, and a tiltable member mounted on the other end of each of said arcuate arms to be successively engaged by said projections as said casing rotates to successively pivot said arms against the action of said resilient means, right angular lips formed on the ends of said strap member and spaced from the outer peripheries of said arms, and laterally extending projections formed on the outer peripheries of said arcuate arms on the sides of the pivots of said arms opposed to the points of attachment of said resilient means to engage the adjacent sides of said lips and limit the action of said resilient means in pivoting said arms.
